UNITED STATES PATENT OFFICE.

CHARLES G. PFEIFFER, OF PHILADELPHIA, PENNSYLVANIA, ASSIGNOR TO SPECIALTY ENGINEERING COMPANY, OF PHILADELPHIA, PENNSYLVANIA, A CORPORATION OF PENNSYLVANIA.

GRAVITY CHUTE.

Application filed October 24, 1927. Serial No. 228,290.

This invention relates to gravity chutes, more particularly to those of a spiral type useful in continuously conducting granular or pulverulent materials such as coal, gravel, sand, powder, etc., from higher to lower levels.

The aim of my invention is to provide a compact conveyor of the above character composed of interchangeable volute sections adapted to be secured together end for end and so configured transversely as to form, when assembled, a structure which is entirely self-sustaining, i. e. capable of maintaining its integrity without requiring either an axial column or pillars externally thereof to support it against sagging or collapsing under load.

The advantages accruing to my invention will be manifest from the detailed description of the typical embodiment shown in the drawings whereof, Fig. I is a plan view of the spiral chute.

Fig. II is an elevation of the same; and Fig. III is a detail illustration showing the transverse configuration of the volute sections of which the structure is made up.

As herein depicted, my improved spiral chute embodies a multiplicity of interchangeable volute sections 5—5 which are troughed to the angular configuration shown in Fig. III to provide the conveying channel or raceway 6. The bottom 7 of the raceway 6 is inclined somewhat to the horizontal, upward from its inner spiral edge at 8. The upper standing flange 9 of the trough meets the bottom 7 in a well rounded curve 10 with avoidance of sharp corners and imposition of undue restraint against the free flow of the material in the trough. Along the inner spiral edge 8, each section 5 is provided with an integral drop flange 11, for a purpose to be later on explained. As shown in Fig. I the sections 5—5 extend over a quadrant and meet end to end along radial planes at right angles. At their ends, the sections 5 are moreover provided with integral securing flanges 12, 12 adapted to abut in the juncture planes and which extend inward into merger with the drop flanges 11. As shown, the abutment flanges 12, 12 are pierced at suitable intervals for passage of the securing bolts 13.

When the several component sections 5 of the chute are assembled and secured together in the manner explained, it will be apparent that the drop flanges 11 jointly constitute a spiral stiffening internally of the structure while the abutting flanges 12, 12 serve, at the same time, to brace it transversely. In practice a sufficient number of the sections 5 are joined together to form a raceway of the desired height, whereupon the end sections are secured to the upper and lower levels between which the material is to be conveyed,—no other support or scaffolding being necessary to sustain the structure against collapse under load by virtue of the longitudinal and transverse bracing afforded by the flanges 11, 12.

I have thus provided a spiral conveyor which is extremely simple in construction; very economical to manufacture; and easy to erect. The structural simplicity characteristic of my invention is also conducive to ready replacement of sections which have become badly worn after extensive usage, so that upkeep expenses are reduced to the very minimum.

Having thus described my invention, I claim:

1. A spiral gravity chute embodying interchangeable angularly-troughed volute sections adapted to be secured together end for end, said sections having integrally-formed depth flanges jointly constituting a spiralized stiffening whereby the structure is rendered self-sustaining under load.

2. A spiral gravity chute embodying interchangeable angularly-troughed volute sections adapted to be secured together end for end, said sections having integrally formed depth flanges at their inner edges jointly constituting a spiralized internal stiffening whereby the structure is rendered self-sustaining under load.

3. A spiral gravity chute embodying interchangeable angularly-troughed volute sections integrally formed with end securing flanges adapted to abut radially of the chute structure and to brace it crosswise, and depth flanges intersecting with said securing flanges to constitute a spiralized stiffening whereby the structure is rendered self-sustaining under load.

4. A gravity chute embodying interchange-

able angularly-troughed volute sections with integral end securing flanges adapted to abut radially of the chute structure and brace it crosswise, as well as with integral depth flanges at their inner edges that intersect with the radial flanges aforesaid and constitute a spiraled internal stiffening whereby the

structure is rendered self-sustaining under load.

In testimony whereof, I have hereunto signed my name at Philadelphia, Pennsylvania, this 19th day of October, 1927.

CHARLES G. PFEIFFER.
